Primary Examiner — Janice Seeger(74) *Attorney, Agent, or Firm* — Maschoff Gilmore & Israelsen**CLAIM**

The ornamental design for a table top, as shown and described.

DESCRIPTION

FIG. 1 is an upper perspective view of an exemplary table top; FIG. 2 is a rear view of the table top shown in FIG. 1; FIG. 3 is a left side view of the table top shown in FIG. 1; FIG. 4 is a top view of the table top shown in FIG. 1; FIG. 5 is a right side view of the table top shown in FIG. 1; FIG. 6 is a front view of the table top shown in FIG. 1; and, FIG. 7 is a bottom view of the table top shown in FIG. 1. The broken lines shown in the figures are for illustrative purposes only and form no part of the claimed design.
